SILK SCREEN STENCIL APPARATUS

James A. Black and Edwin A. Steuten, Grand
Rapids, Mich., assignors to Continental Decal-
comania Company, Grand Rapids, Mich., a cor-
poration of Michigan

Application June 21, 1947, Serial No. 756,168

2 Claims. (Cl. 101—415.1)

1

The present invention relates to silk screen stencil apparatus, and the primary objects of the invention are to provide a silk screen stencil and a mounting frame therefor of novel construction whereby the stencil may be quickly and easily mounted on or demounted from the frame, and whereby the stencil when mounted on the frame may be adjusted as to tension and may also be adjusted with respect to its relative position in the frame; to provide such a silk screen stencil mounting frame which may either be used in the process of silk screening by hand, or which may be incorporated in an automatic silk screen stencilling machine and when so incorporated in a machine lends itself readily to the interchanging of stencils so that successive stencils used in multicolor printing of a batch of stock may each be quickly and easily brought into registry with the preceding run or runs of the stock for different colors; to provide such a stencil and stencil mounting frame construction which when the stencil is mounted on the frame forms a seal around the edges of the frame so that coating material cannot escape from between the stencil and the frame; to provide such a stencil and frame therefor which may be used in the printing of posters, decalcomanias, plywood panels or other items which lend themselves to silk screen process coating; and to provide such a stencil frame which is rigid and sturdy in construction, efficient in its intended use, and reasonably economical in manufacture.

These and other objects hereinafter appearing are attained by, and the invention finds preferable embodiment in, the structure or device particularly described herein and illustrated by the accompanying drawings, wherein:

Figure 1 is a perspective view of the silk screen mounting frame, with a silk screen stencil secured thereto on three sides or edges, the fourth side or edge being shown in a position preparatory to being secured to the fourth side of the frame;

Figure 2 is an enlarged, fragmentary view of the same shown in section taken on line 2—2 of Figure 1;

Figure 3 is an enlarged, fragmentary view of the same shown in section taken on line 3—3 of Figure 1;

Figure 4 is a fragmentary perspective view of a corner of the mounting frame and a corner of the silk screen stencil, showing one edge of the stencil secured to the frame and another edge in the process of being so secured to the frame; and

Figure 5 is a top plan view of the mounting frame and silk screen applied thereto and show-

2

ing a card previously printed with one color in position beneath the frame and stencil.

Referring now in detail to these drawings, wherein like parts are designated by the same numerals in the several views, the silk screen stencil mounting frame generally designated 10 comprises an open rectangular framework fabricated from wooden side rails 11 having a special cross section best illustrated in Figures 2 and 3. The inner side 12 of each rail is vertical and the top 13 of each rail is horizontal. The outer side 14 of each rail is shaped to form an upper shoulder 15 and a lower shoulder 16, and the bottom 17 of each rail slopes downwardly and inwardly as shown.

Swing plates 18 are mounted for swinging movement about the outer and upper edge of the sides of the framework by means of hinges 19, the lower or inner leaves of which hinges are secured to the upper shoulders 15 of the side rails 11 by means of wood screws 20. The swing plates 18 are preferably of metal and are secured as by spot welding to the upper or outer leaves of the hinges 19. The outer or free edges of the swing plates 18 are provided with open-seam metal tubes 21 either welded thereto or formed integrally therewith as shown. Thumbscrews 22 threaded through the swing plates are adapted to abut at their inner ends against the lower shoulders 16 of the framework's side rails 11 or, and preferably, against metal inserts 23 threaded in the shoulders 16 and provided with sockets 24 in their heads 25 in which sockets the inner ends of the thumbscrews seat. Metal rods 26 having smooth rounded ends are adapted to slide within the open-seam tubes 21 with sufficient clearance therebetween to accommodate hems 27 sewn in the marginal edges of a rectangular silk screen stencil 28. The corners of the stencil are cut away to provide open ends for the hems 27.

The silk screen stencil 28 is mounted on the mounting frame 10 by being stretched across the underside of the wooden framework. The stencil is then secured to the mounting frame by lowering each swing plate 18 and inserting the smooth end of a rod 26 into the open end of a hem 27 of the stencil and then into the open end of the adjacent tube 21, with the end of the hem surrounding the rod and said hem extending outwardly through the open seam of the tube as illustrated in Figure 4. Because the metal parts and the silk of the stencil are smooth, insertion of the rod within the tube draws the hem into the tube as the rod progresses, and the complete insertion of the rod within the tube with the hem

of the stencil therebetween is quickly, smoothly and easily accomplished.

After the four edges of the stencil 28 have thus been secured to the respective swing plates 18, the thumbscrews 22 are turned down by hand thus effecting slight swinging movements of the swing plates for adjusting the tension on the silk screen stencil as required.

The swing plates 18 and thumbscrews 22 may also be employed to shift the silk screen stencil's position relative to the mounting frame 10. This is especially important when the frame and stencil are mounted on a machine having stops or other means for positioning sheets of stock therein in exactly the same position they occupied during a previous run through the machine, because it is important that all runs of different coating materials, different colors and different designs be brought into registry on the stock. In Figure 5 is illustrated an octagonal sheet of stock on which has previously been printed a large circle 30 indicated in dotted lines, and which previously printed circle may for purposes of illustration be said to be yellow. For further illustrative purposes, the stencil now in the screen may be said to be for applying blue color, it being intended that a small circle be stencilled in blue through the small circle cutout 31, while the large circle 30 is intended to be green on the finished sheet of stock. As illustrated, the screen 28 is not now in the proper position of registry for screening a large blue circle through the cutout 32 onto the previously printed yellow circle 30 in order to produce a green circle. It will readily be seen, however, that by slightly loosening the thumbscrews 22¹ along the upper and left hand sides of the mounting frame as viewed in Figure 5, and by correspondingly tightening the thumbscrews 22² along the bottom and right hand sides of the frame as illustrated, the large circle cutout 32 of the screen 28 may quickly and easily be brought into registry with the printed yellow circle 30 on the sheet of stock so that the desired result will be obtained.

It will thus be seen that a novel and efficient silk screen stencil and stencil mounting frame have been provided by this invention, and while but one specific embodiment of the invention has been herein shown and described, it will be understood that numerous details of construction may be altered or omitted without departing from the spirit of the invention as the same is defined by the following claims.

We claim:

1. A stenciling apparatus of the silk screen type comprising a mounting frame, a flexible fabric stencil screen extensible across the frame at the underside thereof and adapted to contact a side of the frame, the screen having an edge portion formed with an open-end hemmed margin, an elongated substantially rectangular plate of a length substantially equal to the length of a side of the frame, said plate being hinged along a longitudinal edge portion thereof to said side of the frame at its upper outer edge on a line re-

mote from the line of contact between the fabric screen and the adjacent underside of the frame, the hinged plate having at its free edge a longitudinally extending open-end tubular part fixedly secured thereto, said tubular part having a restricted longitudinal opening therein, a rod with a smooth end and a diameter conformable with the interior of the tubular part and larger than the restricted longitudinal opening in the tubular part for insertion into the hemmed margin of the fabric screen while within said tubular part for retaining the hemmed margin within the interior of the tubular part, and thumb screws threaded through openings formed in said plate with the ends of the screws in contact with the outer face of the adjacent side of the frame for causing the plate to swing outwardly from the frame to impose tension on the fabric screen.

2. A stenciling apparatus of the silk screen type including a rectangular mounting frame, a rectangular flexible fabric stencil screen adapted to be stretched across the frame at the underside thereof in engagement therewith, said fabric screen having its four edge portions each formed with an open-end hemmed margin, an elongated substantially rectangular plate hinged along a longitudinal edge portion thereof to each side of the frame at the upper outer edge thereof on a line remote from the line of contact between the fabric screen and the underside of the adjacent side of the frame, each of said plates being of a length substantially equal to the length of the side of the frame to which it is hinged, and each of the hinged plates having at its free edge a longitudinally extending open end tubular part fixedly secured thereto, the tubular part having a restricted longitudinal opening therein, rods each with a smooth end and a diameter conformable with the interior of the tubular parts and larger than the restricted longitudinal openings in the tubular parts for insertion into the hemmed margins of the fabric screen while within said tubular parts for retaining the hemmed margins within the interior of said tubular parts, and a plurality of thumb screws threaded in said plates with the ends of the screws engaging the outer side faces of the sides of the frame for imparting an arc-like movement to said plates and imposing tension upon the fabric screen.
